UNITED STATES PATENT OFFICE

JAMES C. DAWSON, OF WEBSTER GROVES, MISSOURI, ASSIGNOR TO ELMA N. DAWSON, OF WEBSTER GROVES, MISSOURI

LOOSE LEAF BINDER

Application filed February 28, 1931. Serial No. 519,135.

This invention relates to loose leaf binders and has for its principal object to improve the means for attaching certain types of "metals" to the backs and also to give a better mounting for the booster levers for opening the rings. While the improved features are applicable to other types of "metals", they are especially advantageous with the cheaper ring book metals in which a single arched plate forms the main body member and the cover plate as well. Ordinarily, such metals are attached to the base plate of the cover by vertical rivets, but this is open to many familiar objections.

According to this invention, each end of the metal is provided with a fitting that permits the book binder to use the same cover attaching means as is used with more expensive metals, serves to strongly bind the ends of the metals to the cover base, and provides a ready and firm support for the booster lever, the lack of which with this type of metal has ever been an annoyance. Having toolled up to make the fittings for the cheaper metals, a manufacturer can readily and economically extend their use to the more expensive binder metals.

The recited objects and others will become apparent from the specification and the annexed drawings, in which

Fig. 1 is a perspective view of a loose leaf binder incorporating the invention;

Fig. 2 is a vertical, longitudinal section of the end portion of the binder;

Fig. 3 is a transverse, vertical section on the line 3—3 of Fig. 1;

Fig. 4 is a bottom plan view of the end of the binder;

Fig. 5 is a detail of a modification showing the booster support in vertical, longitudinal section;

Fig. 6 illustrates in perspective the booster lever and booster lever support;

Fig. 7 is a transverse, vertical section through a modified form of the device, taken adjacent the end of the binder and looking outwardly;

Fig. 8 illustrates in perspective the parts shown in Fig. 7;

Fig. 9 is a bottom plan view showing a

further modification of the booster lever, applied to the binder;

Fig. 10 illustrates in perspective the parts shown in Fig. 9;

Fig. 11 illustrates the booster lever and booster lever support as modified for use with binders of the spring back type;

Fig. 12 shows in vertical, longitudinal section the booster lever and booster lever support applied to spring back binders;

Fig. 13 illustrates a booster lever support adapted to be inserted in binders of the spring back type; and

Fig. 14 illustrates a further modification of the support applied to binders of this type.

The binder, generally indicated by 10, comprises a spring cover plate 11 having hooked margins 12 and 13 in which are retained the articulated toggle plates 14 and 15 which bear paper-holding prongs 16 and 17.

In Figs. 3 and 4, it will be seen that the hooked margins 12 and 13 also engage the outer edges of the tongue 18 of a booster lever support 19. Preferably the tongue has a transverse curvature substantially corresponding to that of the book back 21 adapting it to lie closely against the back. An aperture 22 is cut through the central portion of the tongue through which the loop 23

struck up from the book back projects. A portion 24 of the support 19 is bent substantially at right-angles to the axis of the tongue 18 and forms a close fitting end closure for the binder mechanism. Slots 25 and 26 are cut in the end closure.

The booster lever 27 comprises a thumb arm 28, a fulcrum portion 29, a connecting arm 30 and an operating arm 31. The fulcrum portion 29 fits within the slot 25 and consequently the lower margin of the slot supports the booster lever. Support is given across the whole extent of the fulcrum portion 29 when the thumb arm is flat,

but as shown in the figures the arm 28 and with it the fulcrum portion 29 may be curved for the sake of appearance. In this case, the points of support are at the outer extremities of the portion 29.

I prefer to form a cover retaining or supporting shoulder 32 upon the booster sup-

90

95

100

port by turning it inwardly along an arc corresponding to the transverse curvature of the cover plate. A shoulder 32 may either overlie the cover plate as indicated in Figs. 2 and 5, or pass under it, as shown in Fig. 5. The latter construction has the advantage of stiffening the cover plate where it is most frequently bent by operators pushing upon the cover plate instead of upon the booster levers.

With either arrangement, the shoulder 32 overlies a small end portion of the toggle plates 14 and 15. There is, consequently, no danger that an upward jerk upon the prongs 16, 17 will snap the tongue out from engagement with the hooked margins 12 and 13 of the cover plate.

In assembly, the toggle plates are either sprung into the retaining spring or the spring is rolled down about them, producing a sub-assembly which possesses neither booster levers nor supports. The booster lever is then inserted through the slot 25, and the assembly pushed into the end of the loose leaf binder. The configuration of the booster lever is such that it is retained in position by the engagement of the connecting arm 30 with the inner face 36 of the booster support. Preferably, the slot 25 is located above the toggle plates 12 and 13 and the arm 30 extends across their ends while the operating arm 31 extends beneath the plates to lift them.

If small notches 33 are cut in the tongue, the cover may be bent into them as indicated at 34, 34, Fig. 4, which will prevent the supports and booster levers being displaced when the binder metals are shipped and before they are assembled to the book backs.

Upon assembly to the book back, the binder is placed so that the apertures 22 pass over the loops 23 and a key 35 is driven through the slot 26 and under the loop to lock the assembly in position.

In the modification illustrated in Figs. 7 and 8, the booster lever support 37 carries two small inwardly extending lugs 38, 38 which replace the shoulder 32 of the other supports. The booster lever 39 is slotted at 40, 40 to give clearance to the lugs 38, 38. As indicated, the slot is cut both into the horizontal body portion 41 and into the vertical connecting arm 42. The lever is fulcrumed along the underside of the body portion 41 which engages the margin 43 of the end closure portion 44. If the booster lever 39 be flat, support is given to the entire body portion 41. Preferably, however, the thumb arm 45 and the body portion 41 are curved, and as a consequence, the lever is fulcrumed only adjacent the inner ends of the slots 40, 40. The lugs 38, 38 may either extend over the cover plate 46, as shown in Fig. 7, or beneath the plate to give it extra support.

In the modification illustrated in Figs. 9 and 10, the thumb arm 47 of the booster lever

48 is reduced in size and is assembled by passing it outwardly through the slot 49 in the booster support 50 instead of passing it inwardly as must be done with the forms illustrated in Figs. 2, 3 and 4. The wings 51, 51 may be formed upon the connecting arm 52 to prevent the booster from sliding out through the slot 49 before assembly. After assembly, the booster is held in position between the end closure 53 and the toggle plates. 75

As before stated, it is to the manufacturers advantage to apply such booster supports to binders of the spring back type as well. A support adapted for such binders is illustrated in Figs. 11, 12 and 13 and comprises, 80 as before, a tongue 54, a closure 55, and a shoulder 56. Preferably, the transverse dimension of the tongue 54 is narrower than that of the types previously indicated, so that ample clearance may be given to the 85 toggle plates. An aperture 57 is formed in the tongue and engages the loop 58 struck up from the book back 59.

It is not necessary that the booster supports be provided with a slot in which the boosters are pivoted, for, as indicated in Figs. 7, 8 and 14, the booster may be pivoted upon the upper margin of the closure 37 or 60 and retained against displacement by the cover plate 46 or 61. I prefer the other forms, 95 however, since with a shoulder upon the fitting, there is no danger of the binder coming loose.

I claim:

1. In a loose leaf binder, a plate arched 100 transversely with the sides turned inwardly, prong-bearing toggle members articulated at their adjacent edges to form a toggle joint and having their remote edges mounted to rotate on the inturned sides of the plate, a fitting extending beneath the toggle members and engaging with the inturned sides of the plate, and a booster lever fulcrumed on the fitting and having one arm cooperating with the toggle joint to open the prongs. 110

2. In a loose leaf binder, a plate arched transversely with the crown up and the sides turned inwardly, prong-bearing toggle members articulated at their adjacent edges to form a toggle joint and having their remote edges mounted to rotate on the inturned sides of the plate, and a fitting comprising a body member engaging with the inturned sides of the plate and adapted to cooperate with attaching means for a cover. 115

3. In a loose leaf binder, a plate arched transversely with the sides turned inwardly, prong-bearing toggle members articulated at their adjacent edges to form a toggle joint and having their remote edges mounted to 125 rotate on the inturned sides of the plate, a fitting comprising a body member engaging with the inturned sides of the plate and adapted to cooperate with attaching means for a cover, an upturned end on the body 130

member and a booster lever fulcrumed on the end of the fitting and cooperating with the toggle members to open the prongs.

4. In a loose leaf binder, a plate arched 5 transversely with the crown up and the sides turned inwardly, prong-bearing toggle members articulated at their adjacent edges to form a toggle joint and having their remote edges mounted to rotate on the inturned sides 10 of the plate, a fitting comprising a body member engaging with the inturned sides of the plate and adapted to cooperate with attaching means for a cover, an upturned end on the body member and a booster lever extending through a slot in the upturned end 15 and having one arm extending beneath the toggle plates to lift them.

5. In a loose leaf binder, a plate arched 20 transversely with the crown up and the sides turned inwardly, prong-bearing toggle members articulated at their adjacent edges to form a toggle joint and having their remote edges mounted to rotate on the inturned sides 25 of the plate, a fitting comprising a body member engaging with the inturned sides of the plate and adapted to cooperate with attaching means for a cover, and a booster lever fulcrumed on the end of the fitting and 30 cooperating with the toggle members to open the prongs.

6. In a loose leaf binder, a plate arched 35 transversely with the crown up and the sides turned inwardly, prong-bearing toggle members articulated at their adjacent edges to 40 form a toggle joint and having their remote edges mounted to rotate on the inturned sides of the plate, a fitting comprising a body member engaging with the inturned sides of the plate and adapted to cooperate with attaching 45 means for a cover, and an upturned and slotted end on the body member having an inwardly directed flange telescoping with the end portion of the plate.

7. In a loose leaf binder, a plate arched 50 transversely with the crown up and the sides turned inwardly, prong-bearing toggle members articulated at their adjacent edges to 55 form a toggle joint and having their remote edges mounted to rotate on the inturned sides of the plate, a fitting comprising a body member engaging with the inturned sides of the plate and adapted to cooperate with attaching 60 means for a cover, an upturned and slotted end on the body member having an inwardly directed flange telescoping with the end portion of the plate, and a booster lever extending through a slot in the upturned end and having one arm cooperating with the toggle joint to open the prongs.

8. In a loose leaf binder, a plate arched 65 transversely with the crown up and the sides turned inwardly, prong-bearing toggle members articulated at their adjacent edges to form a toggle joint and having their remote edges mounted to rotate on the inturned sides

of the plate, a fitting comprising a body member engaging with the inturned sides of the plate and adapted to cooperate with attaching means for a cover, and an upturned and slotted end on the body member having an inwardly directed flange telescoping with the end portion of the plate and a booster lever extending through the slot and engaging the toggle plates and engaging their outer margin.

9. Means for attaching booster levers to a loose leaf binder comprising a support adapted to fit within the binder having a back-engaging portion, a booster support portion, and a cover plate engaging portion 80 and provided with an aperture adapted to give clearance to a retaining loop.

10. In a loose leaf binder having toggle plates, a booster lever support having a slot 85 therein, a booster lever pivoted therein, an arm on said lever to engage the toggle plates, and a portion of the lever engaging the face of said support to maintain the lever within the binder.

11. In a loose leaf binder, an arched spring, 90 toggle plates mounted in said spring, a support for a booster lever having a tongue parallel to the toggle plates, a portion normal thereto having a slot therein, a booster lever pivoted in said slot and a portion of the 95 booster preventing the outward longitudinal movement of the lever.

12. A loose leaf binder including an arched 100 spring and toggle plates mounted therein, a book back provided with a retaining loop, a support having a tongue provided with an aperture adapted to engage the loop, and a booster lever in said support.

13. A loose leaf binder having a book back 105 provided with a retaining loop, a spring back having an aperture cooperating with the loop, a support having a tongue cooperating with said loop whereby said support is retained against longitudinal movement, and a booster lever pivoted upon a portion of the 110 support angularly disposed to the tongue.

14. In a loose leaf binder of the type including a plate having marginal flanges and toggle members bearing against the flanges and articulated to form a toggle joint, the combination of a booster lever having a lifting arm to operate the toggle members, a supporting member extending between the flanges and below the toggle members, means for securing the supporting member in place 115 and means on the supporting member to form a fulcrum for the booster lever and to retain it in position.

In testimony whereof I affix my signature.

JAMES C. DAWSON.
